UNITED STATES PATENT OFFICE.

BISUTTI PIETRO FU NATALE, OF PORDENONE, ITALY.

CEMENT-MOLDING APPARATUS.

Application filed May 21, 1926. Serial No. 110,686.

This invention relates to a cement molding apparatus.

Objects of this invention are to provide a cement molding apparatus, such for instance, 5 as a block molding apparatus which may be used to rapidly produce cement blocks in a highly efficacious manner.

Further objects are to provide a cement molding apparatus which is so constructed 10 that any one of a plurality of different types of blocks may be made by this device, and more specifically, it is an object of this invention to provide a novel form of cement block molding apparatus in which the body 15 portion is provided with a plurality of apertures adapted to receive tongues of removable members for shaping or contouring the particular type of block formed by the apparatus, so that the main body portion may 20 be used with any set of cores or other members of this type.

Further objects are to provide a cement molding box in which a movable bottom is provided so that the bottom may be moved 25 slightly after the box has been inverted in order to free it from engagement with the cement, and to provide a novel means for the box to facilitate turning the box over without jar to the contents thereof, and without 30 requiring the operator to lift the weight of the box and the cement therein.

Embodiments of the invention are shown in the accompanying drawings, in which:

Figure 1 is a view from the under side 35 of the box.

Figure 2 is a view from the upper side of the box.

Figure 3 is a transverse sectional view on the line 3—3 of Figure 2.

Figure 4 shows the box provided with a 40 different form of core and with division plates.

Figure 5 is a view showing a further arrangement of cores within the box.

Figure 6 is a view showing a still further arrangement of cores and division plates.

Referring to the drawings it will be seen 50 that the box is provided with a body portion 1 of rectangular contour. The box is provided with angular guides or strips 4 adjacent its lower side edges as shown most clearly in Figures 1 and 3. Between these guides or strips, a movable bottom 5 is slidably positioned, and is adapted to be slid longitudinally of the box when desired as described

in detail hereinafter. The bottom is provided with transverse end bars 2 which are equipped with spherical feet 3. It is to be noted that the guides 4 are cut out as indicated at 4' at one end to accommodate one of the transverse bars 2. This construction insures the entering of the bottom only from one end of the box, and also limits the motion of the bottom in one direction to thus 60 properly position the slots hereinafter described. The bottom of the box is provided with a plurality of parallel slots 6 as shown in Figures 1 and 2, and the ends and sides are similarly provided with parallel slots 7 65 as shown in Figure 3. These slots are adapted for the reception of tongues carried by the cores and other members, as will appear as the description proceeds. For example, when it is desired to form blocks with a hollow, 70 interior cavity of rectangular contour, a core such as indicated by the reference character 8 in Figures 1 and 3 may be provided. This core is a hollow metal member with a closed top and tapers upwardly and has a plurality 75 of tongues or ears 9 which are pressed through the corresponding slot 6 in the bottom of the box. These ears are preferably apertured and receive locking pins 10.

Other types of cores may be provided, for 80 example as shown in Figures 2 and 3. The corners of the block may be cut away by means of a corner core 11, such corner core being provided with a bottom tongue, if desired, or else with a laterally extending 85 tongue 12 as shown most clearly in Figure 3. This tongue passes through a slot in the side wall of the box and is locked in place by means of a locking pin as shown in Figures 2 and 3. Further, if it is desired to 90 form a cut out at the end of the block, this may be readily produced by means of the curved end core member 13 shown in Figure 2, such end core member being provided with 95 tongues or ears 14 passed through the appropriate slots in the end of the mold or box, which are similarly locked in place by means of pins.

The box is provided on one side with a pair 100 of curved straps or supporting members 15.

In using the box, it is merely necessary 105 to fill it with cement, or any suitable mixture of this type, and to thereafter "cut it off" across the top in the usual manner. Thereafter, the box is tilted sidewise,—to the 110 left, as shown in Figure 3, so that it rolls upon the side support 15. This rolling mo-

tion may be continued until the box is inverted. Thereafter, the bottom is slid a slight distance to loosen the central core and also to free the bottom from the cement. The box, obviously, may be tapped to further free it from the cement, and thereafter, it is drawn directly upwardly by means of the handles 16, thus leaving a completely shaped and finished block in position for subsequent drying.

It is to be noted particularly that this type of molding apparatus permits the formation of a multitude of different shaped blocks from one device. For example, as shown in Figure 4, a six-sided core 17 may be positioned within the box. This core as well as all of the cores employed with this apparatus may be provided with apertures to receive clamping bolts 18 as shown in Figure 4. These clamping bolts may be employed to lock division plates 19 in place as shown in Figure 4. These division plates may extend, for example, transversely from the core to the sides of the box, and thus, when the device is assembled, as shown in Figure 4, the box may be used to form half blocks.

Other forms of blocks may obviously be made in a similar manner, for example, by using cores as indicated at 20 and 21 in Figure 5.

Further, it is to be noted from reference to Figure 3 that the ends of the body portion may be provided with notches 22 at their top edges. These notches are adapted to receive the tongues 23 of the division plates 24 which extend lengthwise of the box. These division plates, therefore, may be used to divide the box longitudinally so that a plurality of relatively thin elongated blocks or slabs may be formed. Obviously, it may be desired to produce slabs whose thickness is not an even division of the width of the box. Under these conditions, it is merely necessary to bolt a narrow flanged plate 25 to one of the division plates 24 as shown in Figure 6. In this way, the cement is prevented from being deposited in the unused space, for instance, the space indicated by the reference character 26 in Figure 6. Thus in all forms of the invention, the cement may be placed directly in the box and thereafter the top may be scraped even with the top

of the box and the blocks finished in the manner described in detail above.

It will be seen that a novel form of cement molding apparatus has been provided by this invention which may be rapidly employed for producing a large number of blocks in a short interval of time. It will be noted also that a minimum effort on the part of the operator is required in using this device.

It is to be noted further that a simple type of apparatus for molding cement has been provided, which although of relatively simple construction, nevertheless, will produce a multitude of different shaped blocks in a rapid and easy manner.

Although the invention has been described in considerable detail, such description is intended as illustrative rather than limiting as the invention may be variously embodied and as the scope of such invention is to be determined as claimed.

I claim:

1. A cement molding apparatus comprising an open topped body portion having a bottom provided with apertures, a core adapted to rest upon said bottom and having tongues adapted to project through said apertures, means for locking said tongues in place, and division plates removably secured to said core.

2. A cement molding apparatus comprising a body portion having vertical walls and a slidable bottom, said bottom being carried in guiding members extending along opposite bottom edges of the body portion, said guiding members being notched at one end, a transverse member carried at one end of said bottom and adapted to fit said notches to determine the position of the bottom and to prevent reverse insertion thereof, said bottom having a plurality of apertures therethrough, and interchangeable core members having tongues adapted to be inserted through said apertures, whereby said core members will be definitely positioned with reference to said body portion when said bottom is slid into position.

In testimony that I claim the foregoing I have hereunto set my hand at Milan, Italy.

BISUTTI PIETRO RU NATALE.
